CLAIM

The ornamental design for a boring machine with casing driver, as shown and described.

DESCRIPTION

FIG. 1 is a front view of a boring machine with casing driver of my new design, a rear view being a mirror image of the front view;

FIG. 2 is a left view thereof with the 6-6 line;

FIG. 3 is a right view thereof;

FIG. 4 is a top view thereof, a bottom view is omitted because the article is a heavy object;

FIG. 5 is a reference view showing a state of use thereof with the 7-7 line;

FIG. 6 is a cross-sectional reference view taken along the 6-6 line in FIG. 2; and,

FIG. 7 is an enlarged cross-sectional reference view taken along the 7-7 line in FIG. 5.

(Continued)

The broken lines in the figures are for the purpose of illustrating portions of the article that form no part of the claimed design.
